US0D1016999S

(12) **United States Design Patent** (10) Patent No.: **US D1,016,999 S**
(45) Date of Patent: ** Mar. 5, 2024

(54) **WALL MOUNTED HAND SHOWER SUPPORT**

(71) Applicant: **HANSGROHE SE**, Schiltach (DE)

(72) Inventors: **Matthias Oesterle**, Winterbach (DE);
Marco Flraig, Stuttgart (DE)

(73) Assignee: **Hansgrohe SE**, Schiltach (DE)

(**) Term: **15 Years**

(21) Appl. No.: **29/832,498**

(22) Filed: **Mar. 28, 2022**

(30) **Foreign Application Priority Data**

Oct. 4, 2021 (EM) 008714109-0006

(51) **LOC (14) Cl.** **23-06**

(52) **U.S. Cl.**

USPC **D23/304**

(57) **CLAIM**

The ornamental design for a wall mounted hand shower support, as shown and described.

DESCRIPTION

FIG. 1 is a perspective view of a wall mounted hand shower support showing our design;

FIG. 2 is a front elevational view;

FIG. 3 is a rear elevational view;

FIG. 4 is a side elevational view;

FIG. 5 is a side elevational view;

FIG. 6 is a top plan view;

FIG. 7 is a bottom plan view; and,

FIG. 8 is an enlarged view of FIG. 1.

The dot-dash line in FIG. 8 is included for the purpose of illustrating the bounds of the enlarged view and forms no part of the claimed design.

1 Claim, 8 Drawing Sheets
